UNITED STATES PATENT OFFICE

150,287

DESIGN FOR AN ELECTRIC SIGNALLING DEVICE

Gisbert L. Bossard, Cleveland, Ohio

Application July 26, 1946, Serial No. 131,964

Term of patent 3½ years

(Cl. D72—1)

To all whom it may concern:

Be it known that I, Gisbert L. Bossard, a citizen of the United States, residing at Cleveland, in the county of Cuyahoga and State of Ohio, have invented a new, original, and ornamental Design for an Electric Signalling Device, of which the following is a specification, reference being had to the accompanying drawing, forming part thereof.

Fig. 1 is a perspective view of the front of an electric signalling device, showing my new design wherein the design of the side surfaces are identical; and Fig. 2 is a side elevation thereof.

I claim:

The ornamental design for an electric signalling device as shown and described.

GISBERT L. BOSSARD.
